COMBINATION CHAIR AND DROP-LEAF TABLE

Martin Nelson, Menlo Park, Calif.

Application July 3, 1950, Serial No. 171,845

3 Claims. (Cl. 155—123)

1

This invention relates to furniture and more particularly to wooden chairs of the type having a straight back provided with a table-like section for supporting articles such as dishes and the like thereon.

The chair proper embodying the present invention may be of any well known form and construction. However, the chair best adapted for the purpose is of the Swedish peasant type, rustic or modern, such as would be suitable for social gatherings in clubs and other public meeting places, or dens and playrooms of dwellings.

As is often the case in social gatherings or events, foods and beverages are served in an informal manner, as for instance buffet style. At such events the problem of a guest balancing on his knee a service plate while holding a cup or glass is notoriously precarious and often embarrassing, when the guest should be at ease and enjoy his refreshments with comfort and pleasure. It is to this end that the present invention is directed.

From the foregoing it is apparent that this invention has as its object to provide a novel drop leaf table which can be disposed to support receptacles relieving occupants of the chair from holding or otherwise juggling such receptacles.

Another object is to provide a concealed panel in a chair back adapted for horizontal disposition to provide a table.

Yet another object is to provide a chair back which is simple in construction, economical to manufacture, and highly efficient in use.

A further object of this invention is to provide a drop leaf table bracket completely below the table itself so as to render the latter accessible from all sides other than that which is connected to the chair.

A still further object is to provide a recessed chair back having a drop leaf panel hinged thereto for movement into and out of register with the recessed chair back.

These and other objects and advantages of the present invention will become apparent in the following description and claims taken with the drawings in which:

Fig. 1 is a perspective view of a chair embodying the present invention, the legs of such chair being shown fragmentarily.

Fig. 2 is a side view of Fig. 1 taken from line 2—2 thereof.

Fig. 3 is a fragmentary perspective view comparable to that of Fig. 1 with the table portion thereof in position for use.

Fig. 4 is a fragmentary view of the chair of Fig. 3 as seen from above.

The chair proper 10 consists of the usual seat portion 11 having legs 12 which may be joined by the usual cross bracing or tie rods as desired.

Depending upon the style of chair, the seat 11

is either plain, contoured or provided with an applied seat of reed or the like. In all events the perimeter of the seat 11 preferably has the form shown with a rearward extension 13 to provide indented rear edges 15 and 16 at either side of the extension 13.

The chair 10 is provided with a back 20 suitably anchored at its base to the seat 11 slightly forward of the indented rear edges 15 and 16. This leaves a substantial platform 21 rearwardly of the back 20, which platform includes the rearward extension 13 and a part of the seat 11.

The upstanding back 20 is tilted rearwardly and is further supported by a main block or bracket 22 having its base secured by glue and/or dowels to the platform 21 and having its altitudinal edge 23 likewise secured to the rear wall of the back 20.

As is often the case where men are gathered, a man will sit facing the chair back with his legs straddling the same. Thus seated a man may rest his arms on the top of the chair back or his arms are free for gesturing and the like.

The side edges of the chair back 20 are configurated to provide recesses 25 and 26 comparable to the indented rear edges 15 and 16 respectively of the chair seat. The foregoing configuration of the rear edges of the seat and the side edges of the chair back are suited for reversed sitting of an individual. In other words, the side recesses 25 and 26 receive the thighs of the occupant while the indented rear edges permit articulation of the knees of the occupant.

Now then, when the occupant thus seated is served with dishes of food it is most convenient to have the dishes immediately before him. To this end a drop leaf table 30 is provided on the rear face of the chair back at a suitable height to be accessible to the hands of the occupant of the chair.

The drop leaf table 30 comprises a panel 31 having one of its edges 32 connected by hinges 33 to the rear wall of the chair back. The arrangement is such that the panel 31 can be raised into a position in which it is disposed parallel to the chair back 20. Suitable means 35, in the form of a latch finger 36 secured to the rear face of the back for pivotal movement, is provided to latch the panel 31 in such raised position.

The location of the hinges 33 is such that the lower or connecting edge 32 of the panel 31 is disposed in a plane coincident to a horizontal line extended between the upper extremities of the recesses 25 and 26 formed in the side edges of the chair back. Also included in this plane is the upper extremity 37 of the block 22 which forms a brace or bracket between the platform 21 and the chair back.

In this manner the panel, when horizontally

disposed, is suitably situated above the lap of the occupant. The upper surface 38 of the block 22 is provided with a face adapted to support the panel 31 in a horizontal position. In the present case the surface 38 is downwardly inclined in a rearward direction from the upper extremity 37 of the block 22. A supplemental block 42 is suitably secured to the under surface of the panel 31 and this block 42 is provided with a surface 43 adapted to engage the surface 38 of the main block 22. The angular disposition of the faces 38 and 43 relative to the respective blocks on which they are formed is such that when these surfaces engage each other the attaching face 44 of the supplemental block 42 is disposed in a horizontal position. In other words the wedges formed by the two blocks include angles which, when combined, result in a two piece support having a horizontal upper surface 44. In addition to the foregoing it will be noted that the supplemental block 42 extends a substantial distance from the hinge connection of the panel 31, that is to say, the attaching surface 44 of block 42 extends well beyond the supporting surface 38 of main block 22. In this manner the load of the table 30 is transferred via the extended supplemental block 42 to the main block 22.

In this manner the panel 31 to which the surface 44 is secured is maintained in a horizontal position by the combined action of the hinges 37 and the abutting blocks 38 and 42.

As best illustrated in Fig. 4, the chair back 20 is recessed or routed out as at 45, Fig. 3, preferably in a pattern having edges 46 substantially spaced from the outer edges of the chair back. This recess 45 is of a depth comparable to the thickness of the panel 31 so as to receive the latter. Thus the under or outer surface 41 of the panel 31 is disposed to lie flush with the rear surface of the chair back thereby concealing the panel 31. While the hinges 37 are shown to be in full view it will be apparent that they too can be concealed by employing any one of the well known types of concealed hinges available on the market.

As hereinbefore explained, the panel 31 is latched in raised position by the means 35 in which condition the back 20, with panel 31 concealed therein, has the appearance of a plain chair back with a carved groove 46, Fig. 1, designated therein. By the same token the main and supplemental blocks 38 and 42 have the appearance of a continuous bracket with an angular inset 49 as best shown in Figs. 1 and 2.

The chair thus constructed is suitable for use in the conventional manner as a part of a breakfast set or for use at banquet tables. However, at informal gatherings or like occasions when refreshments are served, the latch 35, when released, will allow the panel to drop by its own weight. Thus the chairs of the present invention are provided with a dish support above lap height for ready use by the persons gathered.

Although the straddling of the back of the chair by reverse sitting is advantageous it is apparent that persons seated forwardly on one chair may place their dishes on a table 30 on a chair immediately ahead. Moreover, when several chairs are arranged in a circle, small groups of people can refresh themselves in comfort when their dishes are placed on the table 30 of an adjacent chair.

While I have described my invention specifically and in detail, it will be apparent to those

skilled in the art that certain modifications, alterations and variations in construction can be made without departing from the invention herein. I therefore desire to avail myself of all modifications, alterations and variations as fairly come within the purview of the appended claims.

What I claim as new and desire to protect by Letters Patent is:

1. In a chair of the type having a seat and a back having a panel hingedly mounted thereon for swinging movement between raised and lowered position; the combination therewith of a bracket for supporting said panel in a horizontal position when lowered comprising a main block secured to said chair back and to said chair seat rearwardly adjacent said chair back, said main block having an inclined upper face terminating at the axis about which said hingedly mounted panel swings, a supplemental block having an attaching surface secured to the outer surface of said chair back in alignment with said main block and provided with an inclined surface also terminating at the axis about which said panel swings whereby said main and supplemental blocks present a substantially continuous bracket having an angular inset, said main and supplemental blocks each being of wedge form in which the angle included in each when combined results in disposing the attaching surface of the supplemental block in a horizontal position when said panel is moved into lowered position.

2. In a chair of the type having a seat and a recessed back extending upwardly therefrom a substantial distance inwardly of the rear edge of said seat to leave a platform on the rear edge of said seat and a drop leaf panel hingedly mounted on the rear surface of said seat back for movement into raised position in which its outer surface lies flush with the rear face of said back and into lowered position for extension horizontally from said back; the combination therewith of a bracket comprising a main block secured to said platform and to the rear face of said back and a supplemental block having an attaching surface secured to the outer face of said panel in alignment with said main block, each said main and supplemental block having corresponding opposing angularly disposed faces adapted to engage one another when said panel is lowered to support the same in a horizontal position and to provide an indentation between said main and supplemental blocks when said panel is disposed in raised position, and means on said chair back for latching said panel in raised position.

3. In a chair having a seat and a back disposed a substantial distance inward from the rear edge of said seat to provide a platform adjacent the rear face of said back, said back having inwardly tending arcuated side walls adjacent said seat for receiving the thighs of a person seated on said seat; the combination therewith of a drop leaf table comprising a panel hingedly mounted on said back for pivotal movement about an axis coinciding with a line extending between the upper extremities of said arcuated side walls of said back whereby to dispose said panel just above the thighs of a person seated on said seat when said panel extends horizontally rearwardly of said back, and bracket means comprising a main block secured to said platform and said back and a supplemental block secured to the outer-under surface of said panel to present a

seeming continuous bracket when said panel is in raised position, said main and supplemental blocks having corresponding angularly cut surfaces opposite each other, terminating at the axis about which said panel is pivotally movable, and engageable with each other for providing a continuous support for said panel when the latter is disposed in horizontal rearwardly extending position relative to said back.

10 MARTIN NELSON.
